His Attorney

UNITED STATES PATENT OFFICE

JOHN B. FREYSINGER, OF NEW BRITAIN, CONNECTICUT, ASSIGNOR TO NORTH & JUDD MANUFACTURING COMPANY, OF NEW BRITAIN, CONNECTICUT, A CORPORATION OF CONNECTICUT

AUTOMOBILE DOOR LATCH

Application filed March 6, 1928. Serial No. 259,442.

This invention relates to latches, and has particular reference to latches for use in connection with the doors of automobiles.

The aim of the present invention is to provide a latch which is equally adaptable for use on right and left hand doors so that, from a single stock of latches, the demands or requirements of the various doors of an automobile may be met. Thus, by the present invention, the necessity to manufacture and carry a separate stock of latches for right hand doors and a separate stock for left hand doors, together with the inconveniences and difficulties experienced in manufacturing and distributing the same are eliminated, and the investment and carrying charges are greatly reduced.

A further aim of the invention is to provide an improved automobile door latch which may be interchangeably used on right and left hand doors and wherein the construction is such that looseness and rattling of the parts is eliminated and avoided without the necessity of constructing the parts within very close limits.

A further aim of the invention is to provide a latch of this sort which is characterized by its simplicity in construction, its economy in manufacture, and its effectiveness in operation.

Other objects will be in part obvious and in part pointed out more in detail herein-after.

The invention accordingly consists in the features of construction, combination of elements and arrangement of parts which will be exemplified in the construction herein-after set forth and the scope of the application of which will be indicated in the appended claims.

In the accompanying drawings, wherein I have shown, for illustrative purposes, one of the embodiments which the present invention may take:

Figure 1 is a side view of my improved latch mechanism with one of the side plates of the casing removed;

Fig. 2 is a vertical sectional view taken on line 2—2 of Fig. 1; and

Fig. 3 is a horizontal sectional view taken

centrally through the latch mechanism substantially on line 3—3 of Fig. 1.

Referring to the drawings in detail, the casing, which may, of course, be of any suitable construction, is here shown, by way of illustration only, as comprising an inside plate 10, an outside plate 11 and a front plate 12. The front plate 12 may be formed integrally with the side plate 10, if desired. The plates 10 and 11 are suitably tied together as, for example, by means of a connecting sleeve 13 and turned over lugs 14. In the present instance, the lugs are formed integrally with the plate 11 and extend through openings 15 in the plate 10. The numeral 16 designates a latch or bolt proper which, as usual, extends through an opening 17 in the front plate 12. The rear or inner end of the bolt 16 is bifurcated, as shown, so as to straddle and be guided by the sleeve 13.

In accordance with the present invention, there are provided two roll-backs or levers 20 through the instrumentality of either of which the bolt 16 is adapted to be operated. These roll-backs are symmetrically arranged with respect to the bolt; that is to say, one is located above the bolt and the other similarly located below the bolt with their arms 22 extending away from the bolt. These roll-backs are preferably of identical construction so as to reduce the cost of manufacture. Each has a circular portion which is swaged partly out of the plane of the roll-back so as to form to one side a cylindrical boss 24 and, on the other side, a cylindrical recess 25. The embossed portions have polygonal openings 26 adapted to receive the shank or spindle of the usual operating lever or handle 27. The casing is so constructed that the identical roll-backs 20 may be supported therein in reversed relation.

To this end, the inside plate 10 has an opening 28 adapted to receive and constitute a bearing for the boss 24 of the upper roll-back, and the outside plate 11 has an opening provided with a bearing flange 29 which extends into the cylindrical recess 25 of the upper roll-back. The inside plate 10 has an opening with a flange 30 corresponding to the flange 29 and engaging in the recess 25 of the

lower roll-back, and the outside plate 11 has an opening 31 corresponding to the opening 28 and receiving and constituting a bearing for the cylindrical boss 24 of the lower roll-back. The arms of the roll-backs, when the same are in the inoperated position shown in Fig. 1, are adapted to engage against the shoulder provided by the front plate 12.

The roll-backs are operatively associated with the bolt by a member preferably connected to the bolt and adapted to engage the arms 22 of the roll-backs, the arrangement preferably being such that this member has a limited movement with respect to the bolt in order that, when the parts are in the inoperated position shown in Fig. 1, both of the roll-backs are held between the front plate and the member against rattling, and this result is accomplished although the parts may be made with the usual clearance or relatively large tolerances which are necessary to produce latches of this sort at prices at which they must be sold. This member, designated by the numeral 35, is in the form of a fork and, for convenience, is herein referred to as a compensating yoke. It is pivoted to one edge of the bolt, as at 36, and has a lug 37 engaging in a notch 38 in the upper edge of the bolt. This notch is slightly larger than the lug so that the latter has a limited movement in the former. The ends of the compensating yoke are adapted to engage the arms of the roll-backs, as illustrated.

The latch, together with the parts associated therewith, is normally urged into the inoperated position shown in Fig. 1 by a spring which may take the form of the spring 39 shown in the drawings. Springs of other types, however, may be employed for this purpose.

The latch mechanism may or may not be provided with locking or stop means for preventing withdrawal of the bolt when a turning force is applied to the handle 27. In the present instance, there is shown, for illustrative purposes, a latching means which is in the form of a lever or arm 40 pivoted on a stud or pin 41 and having a stop portion or projection 42 which is adapted to take in behind the yoke 35 when the lever is in the latching position shown in Fig. 1. The pin 41, constituting the fulcrum for the lever 40, is on the medial line of the bolt as illustrated, a feature which is of importance in that, with the pivot so located, certain of the like parts can be used either in right or left hand arrangements. The lever carries a handle or pin 43 which extends through an arcuate slot 44 in the inside plate 10. A spring 45 about the stud 41 may be employed for urging the lever 40 against the inside plate. The lever has a projection or boss 47 adapted to engage in recesses 46 in the plate 10 so as to hold the lever in its respective positions.

It will be seen from the foregoing descrip-

tion, taken in connection with the accompanying drawings, that my improved latch mechanism may be employed on a right hand as well as a left hand door and thus the requirements for latch mechanisms on all of the doors of an automobile may be met from a single stock of latch mechanisms unless one of the doors is to be provided with a key-controlled lock as is the case in sedans. When the latch mechanism is used on a door which swings in one direction, the latch mechanism will be mounted on the door with a given roll-back above the bolt, and when used in connection with a door which swings in the other direction, the latch mechanism is inverted so that that given roll-back will be below the bolt.

The operating handles 27 may be connected to either of the roll-backs, as desired. Owing to the play or loose movement between the bolt and the compensating yoke 35, this yoke will hold both of the roll-backs with substantially equal force against the front plate 12 which constitutes a stop so to speak, thus, when the parts are in the position shown in Fig. 1, the roll-backs are held against loose movement and rattling. As previously observed, the parts may be made with the ordinary leeway or clearances without introducing rattling of the parts.

As many changes could be made in the above construction and many apparently widely different embodiments of this invention could be made without departing from the scope thereof, it is intended that all matter contained in the above description or shown in the accompanying drawing shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

I claim as my invention:

1. In a latch mechanism, a casing, a bolt slidably mounted therein, a pair of roll-backs through either of which said bolt is adapted to be retracted, said roll-backs being symmetrically arranged with respect to and on opposite sides of said bolt, a yoke pivoted to said bolt for pivotal movement with respect to said bolt and said casing and adapted to engage the arms of said roll-backs, and means between said bolt and yoke for limiting movement therebetween.

2. In a latch mechanism, a casing having a front wall, a bolt slidably mounted in said casing; a pair of roll-backs, each having an arm, said roll-backs being symmetrically arranged on opposite sides of and at like distances from said bolt and the arms thereof being adapted to engage said front wall; a yoke

pivoted to said bolt and having limited movement relative thereto, the ends of said yoke being adapted to engage said arms and hold the same against said front wall when the latch mechanism is in normal condition, and a spring urging said bolt to latching position and said yoke against said arms.

3. In a latch mechanism, a casing, a bolt slidably mounted therein, a pair of roll-backs 10 symmetrically arranged on opposite sides of and at like distances from the longitudinal medial line of said bolt and through either of which said bolt is adapted to be retracted, a yoke pivoted to and carried by said bolt 15 and positioned rearwardly of and adapted to engage the arms of said roll-backs, a spring for urging said bolt to latching position and said yoke against said arms, means between said yoke and bolt for limiting the pivotal 20 movement of the former, a pivot member on said casing rearwardly of and on the medial line of said bolt, and a dogging lever pivoted on said pivot member and adapted to engage said yoke to fasten said bolt in latching position.

4. In a latch mechanism, a casing, a bolt slidably mounted therein, a pair of roll-backs journaled in said casing and located one above and the other below said bolt, said roll-backs having identical openings at their centers of oscillation adapted to interchangeably receive the same operating member, said centers of oscillation of said roll-backs being symmetrically arranged with respect to said 35 bolt and at like distances from the medial line thereof, said bolt extending between said roll-backs and a member carried by said bolt and adapted to be engaged by said roll-backs.

5. In a latch mechanism, a casing having 40 a shoulder, a bolt slidably mounted in said casing, a pair of roll-backs journaled in said casing one located above and the other below said bolt and having their centers of oscillation symmetrically arranged with respect to said bolt and at like distances from the medial line thereof, a yoke pivoted to said bolt and having limited movement relative thereto and to said casing, the ends of said yoke being adapted to engage said roll-backs 45 50 and hold the same against said shoulder when the mechanism is in normal position, and means for urging said bolt to latching position and said yoke against said roll-backs.

JOHN B. FREYSINGER.
